QUARTER ADDERS

Theodore H. Bonn and John Presper Eckert, Jr., Philadelphia, Pa., assignors to Sperry Rand Corporation, a corporation of Delaware

Application April 7, 1955, Serial No. 499,808

16 Claims. (Cl. 307—88)

The present invention relates to computing apparatuses and is more particularly concerned with devices capable of performing quarter addition in binary digital applications.

The mathematical process termed "quarter addition" finds its electrical equivalent in the following truth table:

		Input A	
		1	0
Input B	1	0	1
	0	1	0

As will be seen from an examination of the foregoing table, the presence of one or the other, but not both, of two input signals effects an output signal, while the simultaneous presence or absence of the said two input signals results in there being no output signal. Units capable of performing quarter addition in accordance with the preceding truth table form a basic portion of more complex computation devices.

In the past, quarter adders have utilized vacuum tube circuitry for the most part, and have accordingly been subject to the disadvantages that they are relatively fragile in construction and subject to operating failures. The present invention serves to obviate the foregoing disadvantages and, in so doing, provides a quarter adder structure utilizing a pulse transformer as the basic portion thereof.

It is accordingly an object of the present invention to provide improved quarter adders for use in computing applications.

A further object of the present invention resides in the provision of an improved quarter adder device which is more rugged in construction and less subject to operating failures than has been the case heretofore.

Still another object of the present invention resides in the provision of a quarter adder device employing a pulse transformer as the basic component thereof.

A still further object of the present invention resides in the provision of improved devices for performing quarter addition, which devices are selectively responsive to the simultaneity, or lack thereof, of two input signals to produce a characteristic output.

As has been mentioned previously, the present invention, in effecting the foregoing objects, utilizes a pulse transformer, and two signals, which have been termed "Input A" and "Input B" in the truth table given previously, are coupled respectively to the primary side of the said transformer. In practice, the said primary side of the transformer may comprise a single primary winding, in which case the two input pulses may be selectively coupled to opposite ends thereof. However, it should be noted that the said primary side may further com-

prise two windings wound to exhibit opposite polarities respectively and the said two input signals may be respectively coupled to these two windings. It should be understood therefore that in the following discussion, this latter configuration may be substituted for the single primary winding shown, without affecting the operation of the device substantially.

By utilizing the transformer construction mentioned above, the presence of one only of the said two inputs 10 will effect a current flow through the transformer primary winding, or windings, and this current flow will in turn induce a voltage in the transformer secondary. However, if both inputs should be applied to the primary side of the transformer simultaneously, they effectively 15 nullify one another, whereby no voltage is induced in the transformer secondary and no output may be taken therefrom. When so employed, therefore, the pulse transformer configuration of the present invention operates in strict conformity with the truth table given previously.

The foregoing objects, advantages, construction and operation of the present invention will be more readily seen from the following description and accompanying drawings, in which:

25 Figure 1 is a schematic diagram of one form of quarter adder in accordance with the present invention;

Figure 2 is a simplified waveform diagram illustrative of the operation of the device shown in Figure 1, as well of the device shown in Figure 3; and

30 Figure 3 is a schematic diagram of a modified form of quarter adder in accordance with the present invention.

Referring now to Figure 1, it will be seen that, in accordance with one form of the present invention, a pulse transformer T1 may be utilized, having a single primary winding 10 and two secondary windings 11 and 12, which secondary windings are wound at opposite polarity to one another. Again, it should be noted, of course, that the primary winding 10 shown could in fact comprise two windings wound at opposite polarity to one another, in which case the pulse inputs to be described may be coupled to one end respectively of each of the said primary windings, the other ends of the said primary windings being returned to ground. In the specific example chosen, one end of the primary winding 10 is coupled to a terminal 13 connected in turn to a source of selectively applied pulses, hereinafter termed "Input A"; the other end of the said primary winding 10 is further coupled to a terminal 14 which is connected to a further source of selectively applied input pulses, hereinafter termed "Input B." Secondary windings 11 and 12 are each connected via rectifiers D1 and D2, respectively, across a load impedance R_L; and the output of the device is taken at a terminal 15 connected to one end of the said load impedance R_L.

55 Referring now to Figure 2, the operation of the quarter adder shown in Figure 1 will become readily apparent. If we should assume that during a time interval t1, a positive-going Input A pulse is coupled to the primary 10 via terminal 13, there being no further pulse applied 60 to terminal 14, a current will flow through the said primary winding 10, inducing voltages in the secondaries 11 and 12 which voltages are positive on the anode of rectifier D1 and negative on the anode of rectifier D2. Current will therefore flow in the secondary winding 11 through the rectifier D1 and thence through impedance R_L effecting an output pulse at the output terminal 15. Again, if a positive-going input pulse should be applied at terminal 14 during a time interval t2, there being no input pulse at terminal 13 during this time interval, a further current will flow through the primary 10, again 65 inducing voltages in the secondaries 11 and 12, this time

negative on the anode of rectifier D1 and positive on the anode of rectifier D2. Current will therefore now flow through the secondary winding 12 and impedance R_L via rectifier D2; and again an output pulse will appear at the terminal 15. If, however, during a time interval t3, input pulses should be applied to both terminals 13 and 14, the simultaneous voltages so applied to opposite ends of the primary winding 10 will effectively nullify one another and no current will flow through the said primary winding 10 whereby no output appears across load impedance R_L . Thus, an output pulse is obtained at output terminal 15 only when a single input is present at either terminal 13 or terminal 14 on the primary side. Simultaneous application of pulses to both the terminals 13 and 14, or no inputs at either terminal 13 or terminal 14, will result in there being no output pulse at terminal 15. The system thus acts as a quarter adder, in compliance with the truth table given previously.

It should be noted that by the arrangement shown, the polarity of output pulse appearing at terminal 15 is the same whether the input causing the said output pulse is applied at terminal 13 or terminal 14. It should further be noted that inasmuch as current flow through the primary winding 10, due to the application of a single input pulse only, utilizes the other non-pulsed input terminal as the return path therefor, the signal sources coupled to the terminals 13 and 14 should be low impedance sources, and in this respect a low impedance source is defined as one capable of receiving a reverse current flow at its output terminals.

If it is not desired to use the pulse transformer configuration and/or signal sources of Figure 1, an arrangement such as has been shown in Figure 3 may be employed. This modified arrangement utilizes but a single secondary winding and, in addition, may employ high impedance signal sources, in contradistinction to Figure 1, inasmuch as, due to the provision of auxiliary current paths, the signal sources need not accept reverse current flow at their output terminals. The quarter adder shown in Figure 3 again comprises a pulse transformer T3 having a primary winding 30, and a single secondary winding 31. The upper end of primary winding 30 is coupled via a rectifier D6 to an input terminal 32 selectively energized from a source of Input A pulses and the lower end of primary winding 30 is further coupled via a rectifier D7 to an input terminal 33, to which is coupled a further source of selectively applied Input B pulses. The upper end of primary winding 30 is coupled via a rectifier D8 to ground and is further coupled via a resistor R2 to a source of negative potential -V. Similarly, the lower end of primary winding 30 is coupled via a further rectifier D9 to ground and via a further resistor R3 to the source of negative potential -V. The output potentials appearing across secondary 31 of the pulse transformer T3 are applied to a conventional bridge rectifier 34, the operation of which is well known, and the output of the said bridge rectifier is taken across a load resistor R_L at an output terminal 35.

In the absence of input pulses at either terminal 32 or 33, a first current flows from ground via rectifier D8, through resistor R2 to the source of negative potential -V, and a further current flows from ground via rectifier D9 through resistor R3 to the said source of negative potential -V. Thus, in the absence of input pulses at either input terminal, both the upper and lower ends of primary winding 30 are clamped to ground and no output can appear at the terminal 35. If now a positive-going Input A pulse should be applied to terminal 32, this applied pulse raises the upper end of primary winding 30 from ground and a current flows via rectifier D6, primary winding 30 and resistor R3 to source -V. Thus, the application of a single input pulse at the terminal 32 will effect a positive output pulse at output terminal 35. Similarly, if an Input B pulse should be applied to the terminal 33 at a time when there is no input pulse at

terminal 32, the lower end of primary winding 30 will be raised above ground potential and a current will then flow from the said terminal 33 via rectifier D7, primary winding 30 and resistor R2 to source -V. Once more, therefore, a positive-going output pulse will appear at output terminal 35. If, however, there should be a simultaneous application of positive-going Input A and Input B pulses at each of terminals 32 and 33, both the upper and lower ends of the primary winding 30 will be raised to a like potential above ground and no current will flow through the said primary winding whereby there will be no output at terminal 35. Once more, therefore, the device acts as a quarter adder in conformity with the truth table given previously.

It should be noted that the arrangements shown in Figures 1 and 3, may be interchanged as to portions thereof, in dependence upon the particular requirement of the signal input sources, as well as upon the pulse transformer configuration which is to be employed. Thus, either of the primary winding configurations shown in Figures 1 and 3 may be operatively associated with either of the secondary winding configurations shown in those figures, and the operation of the device so formed will be substantially as described in the previous discussion.

Thus, while we have described several embodiments of the present invention, it must be understood that the foregoing description is meant to be illustrative only and is not limitative of our invention. Many variations will be suggested to those skilled in the art, and such variations, which are in accord with the principles discussed previously, are meant to fall within the scope of the present invention, as set forth in the appended claims.

Having thus described our invention, we claim:

1. A quarter adder comprising a transformer having a core of magnetic material, primary winding means and secondary winding means carried by said core and inductively coupled to one another, a first pulse-type signal source coupled to said primary winding means, a second pulse-type signal source coupled to said primary winding means, said first and second signal sources being coupled respectively to opposite ends of a common primary winding, said first source being selectively operative to effect a first current flow in said primary winding means whereby said first current flow induces potentials of a first predetermined polarity in said secondary winding means, said second source being selectively operative to effect a second current flow in said primary winding means whereby said second current flow induces potentials of a second predetermined polarity in said secondary winding means, said first and second signal sources producing signals of like polarity, said first and second pulse-type signal sources being so coupled to said primary winding means that the simultaneous application of pulse signals to said primary winding means from each of said signal sources will produce no resultant current flow in said primary winding means and no resultant flux change in said core and secondary winding means, and means coupled to said secondary winding means and responsive to a resultant potential induced therein due to flow of one or the other of said first and second currents for producing an output signal.

2. The combination of claim 1 wherein clamp means are coupled to each end of said common primary winding for holding each end of said primary winding at substantially ground potential in the absence of a signal applied thereto, respectively.

3. The combination of claim 2 wherein said clamp means comprises first and second diodes coupled respectively between each end of said primary winding and ground, and first and second resistor means coupled respectively between each end of said primary winding and a source of direct potential.

4. A quarter adder comprising a transformer having a core of magnetic material, a primary winding means and secondary winding means carried by said core and induc-

tively coupled to one another, a first pulse-type signal source coupled to said primary winding means, said first source being selectively operative to effect a first current flow in said primary winding means whereby said first current flow induces potentials of a first predetermined polarity in said secondary winding means, a second pulse-type signal source coupled to said primary winding means, said second source being selectively operative to effect a second current flow in said primary winding means whereby said second current flow induces potentials of a second predetermined polarity in said secondary winding means, said first and second pulse-type signal sources being so coupled to said primary winding means that the simultaneous application of pulse signals to said primary winding means from each of said signal sources will produce no resultant current flow in said primary winding means and no resultant flux change in said core and secondary winding means, and means comprising a full wave rectifier coupled to said secondary winding means and responsive to a resultant potential induced therein due to flow of one or the other of said first and second currents for producing an output signal whose polarity is independent of the polarity of potential induced in said secondary winding means.

5. A quarter adder comprising a transformer having a core of magnetic material, primary winding means and secondary winding means carried by said core and inductively coupled to one another, a first pulse-type signal source coupled to said primary winding means, said first source being selectively operative to effect a first current flow in said primary winding means whereby said first current flow induces potentials of a first predetermined polarity in said secondary winding means, a second pulse-type signal source coupled to said primary winding means, said second source being selectively operative to effect a second current flow in said primary winding means whereby said second current flow induces potentials of a second predetermined polarity in said secondary winding means, said first and second pulse-type signal sources being so coupled to said primary winding means that the simultaneous application of pulse signals to said primary winding means from each of said signal sources will produce no resultant current flow in said primary winding means and no resultant flux change in said core and secondary winding means, and means coupled to said secondary winding means and responsive to a resultant potential induced therein due to flow of one or the other of said first and second currents for producing an output signal, wherein said secondary winding means comprises two secondary coils wound at opposite polarity to one another, means coupling one end of each of said secondary coils to one end of a load impedance, and first and second rectifier means respectively coupling each of the other ends of said secondary coils to the other end of said load impedance.

6. The combination of claim 5 wherein said first and second rectifiers are so poled with respect to their corresponding secondary coils that when one of said rectifiers is conductive the other of said rectifiers is non-conductive.

7. A quarter adder comprising a pulse transformer having a single core of magnetic material, and first and second coils inductively coupled to one another and wound on said single core, first and second independent electrical signal sources coupled to opposite ends of said first coil, said signal sources including means producing signals of substantially like potential and energy level, the application of a signal from one only of said signal sources causing a flux change through said coil and core and the simultaneous presence or absence of signals from both of said sources causing no resultant flux change in said coil and core, whereby the application of an electrical signal from one only of said first and second signal sources effects a flux change directly inducing a potential in said second coil, and means coupled to said second coil

and responsive to potentials induced in said second coil for producing an output signal.

8. The combination of claim 7 including clamp means coupled to said first coil, said clamp means providing a return path for current flowing through said first coil due to the application of a signal from one only of said signal sources.

9. The combination of claim 8 wherein said clamp means comprises a pair of diodes coupled respectively between opposite ends of said first coil and a point of substantially ground potential.

10. A control circuit comprising first and second coils inductively coupled to one another, first and second independent electrical signal sources coupled to spaced points on said first coil whereby the simultaneous presence or absence of signals from said first and second sources causes said spaced points to assume substantially like potentials, and the presence of a signal from one only of said signal sources causes said spaced points to assume differing potentials, whereby a current flows in said first coil between said spaced points only in response to occurrence of a signal from one only of said first and second signal sources, clamp means coupled to said first coil for maintaining said spaced points at a predetermined potential level in the absence of signals from said signal sources, and output means coupled to said second coil and responsive to potentials induced in said second coil due to current flow between said spaced points on said first coil, whereby occurrence of a signal from one only of said first and second sources induces a potential in said second coil thereby to directly produce an output signal at said output means and simultaneous presence or absence of signals from both said first and second sources produces no current flow in said first coil and no induced potential in said second coil.

11. A circuit comprising a pulse transformer having a primary winding and a secondary winding, means for coupling a first high impedance pulse-type signal source to one end of said primary winding, means for coupling a second high impedance pulse-type signal source to the other end of said primary winding, a first and a second unidirectional current element, means coupling said unidirectional elements from said ends, respectively, of said primary winding to a point of reference potential, a first and a second resistive element, means coupling said resistive elements from said ends, respectively, of said primary winding to a potential source, and an output circuit coupled to said secondary winding.

12. A device comprising a first clamping circuit and a second clamping circuit, each of said circuits coupled to a fixed reference potential and to a potential source having a certain polarity with respect to said fixed reference potential, a transformer having a primary winding and a secondary winding, said first clamping circuit coupled to one end of said primary winding and said second clamping circuit coupled to the other end of said primary winding, a first pulse-type signal source coupled to said one end of said primary winding, a second pulse-type signal source coupled to said other end of primary winding, each of said signal sources having a polarity opposite to said certain polarity, and an output circuit coupled to said secondary winding.

13. The combination as claimed in claim 12 wherein said output circuit includes rectifying means.

14. A device including first means for receiving a first pulse-type signal having a first polarity with respect to a reference potential, second means for receiving a second pulse-type signal having said first polarity, a pulse transformer having a primary winding and a secondary winding, one end of said primary winding being coupled to said first means, the other end of said primary winding being coupled to said second means, a first and a second biasing means coupling said first end and said second end, respectively, to a voltage source having a

7
polarity opposite to said first polarity, and including separate rectifier means coupling said ends, respectively, to said reference potential, and an output circuit coupled to said secondary winding.

15. A device comprising a pulse transformer having a primary winding and a secondary winding, a first circuit coupled to one end of said primary winding for providing a return circuit at said one end to a point of reference potential in the absence of a first signal of a predetermined polarity applied thereto, a second circuit coupled to the other end of said primary winding for providing a return circuit at said other end to said point of reference potential in the absence of a second signal of said predetermined polarity applied thereto, and an output circuit coupled to said secondary winding.

16. The device as claimed in claim 15 wherein each

5 of said first and second circuits comprise a resistor and a diode means connected in series, and means for applying a voltage thereacross in the forward direction of said diode means, said primary winding ends being respectively connected to the junctions of said diode means and said resistors, said diode means being poled to present back impedances to said first and second signals.
